UNITED STATES PATENT OFFICE.

NAPOLEON B. RIDDLE, OF ST. FRANCISVILLE, LOUISIANA.

RUBBER HEEL.

Application filed October 12, 1926. Serial No. 141,150.

This invention relates to improvements in rubber heels for boots, shoes and the like, and has for one of its objects to provide an article of this character which shall be 5 equipped with an embedded metal anchoring and reenforcing plate adapted, when exposed as the result of the wearing away of the heel, to provide a smooth wear resisting surface that will not scratch or otherwise mar floors and floor coverings.

A further object of the invention is to provide a rubber heel of the character stated wherein the metal plate shall be wholly embedded in the heel and provided with perforations through which portions of the heel pass, such heel portions being adapted to unite and thus prevent the separation of those parts of the heel that are located above and below the plate.

20 A still further object of the invention is to provide a rubber heel of the character stated wherein the metal plate shall be provided with upstanding hollow bosses adapted to wholly house and be engaged by 25 the heads of the elements securing the heel in place, the vertical dimension of the bosses being greater than the corresponding dimension of the heads of the attaching elements so as to avoid any projection 30 of the heads below the plate, and thus prevent the attaching elements from being forced upwardly into the boot or shoe and their heads from scratching or otherwise marring floors and floor coverings, or especially 35 when the plate is exposed as the result of the wearing away of the heel.

With the foregoing and other objects in view, the nature of which will become apparent as the description proceeds, the invention 40 consists of the novel construction, combination and arrangement of parts hereinafter fully described and claimed, and illustrated in the accompanying drawing, wherein:

45 Figure 1 is a sectional view taken on a vertical plane extending centrally and longitudinally through the lower rear portion of a boot or shoe equipped with a rubber heel constructed in accordance with my invention,

50 Figure 2 is a bottom plan view of the parts shown in Figure 1,

55 Figure 3 is a detail plan view of the metal anchoring and reenforcing plate of the rubber heel,

Figure 4 is a view similar to Figure 1 il-

lustrating a slight modification in the manner of securing the rubber heel in place,

Figure 5 is a similar view illustrating a further modification in the manner of securing the rubber heel in place, and

Figure 6 is a similar view illustrating a still further modification in the manner of securing the rubber heel in place.

Corresponding and like parts are referred to in the following description, and designated in the several views of the accompanying drawing, by similar reference characters.

In the drawing, 1 designates the upper, 2 the heel carrying base, and 3 the leather heel lift of a boot or shoe which is shown as being equipped with a rubber heel 4 constructed in accordance with my invention.

The rubber heel 4 is provided with a metal anchoring and reenforcing plate 5. 75 This plate is wholly embedded in the rubber heel 4, and is provided with perforations 6 through which portions of the rubber heel extend. These heel portions unite and thus prevent the separation of those parts of the 80 heel that are located above and below the metal plate 5. Bosses 7 of hollow cylindrical formation are formed integrally with and extend upwardly from the metal plate 5, and are provided at their upper ends with 85 inner annular flanges 8. The bosses 7 terminate short of the upper side of the rubber heel 4, and portions of the rubber heel extend across the upper ends of the bosses. Vertical openings 9 are formed in the rubber heel 4 below the metal plate 5. The 90 openings 9 are arranged in alinement with the bosses 7 and extend through the lower side of the rubber heel 4.

The metal plate 5 strengthens the rubber heel 4, and the bosses 7 are adapted to wholly house and be engaged by the heads 10 of the nails 11 which secure the rubber heel to the leather heel lift 3 of the boot or shoe. The heads 10 of the nails 11 contact 100 with the flanges 8 of the bosses 7, and the openings 9 permit the ready application of the nails.

As shown in Figure 4 screws 12 may be employed for the purpose of securing the rubber heel 4 in place. The heads 13 of the screws 12 contact with the flanges 8 of the bosses 7 and engage internally screw-threaded hollow bosses 14. The bosses 14 are carried by a plate 15 which is secured 110 against the lower side of the leather heel lift 3 by nails 16. The bosses 14 extend

upwardly from the plate 15 and are embedded in the leather heel lift 3.

In Figure 5, the rubber heel 4 is also shown secured in place by screws. The heads 17 of these screws 18 contact with the flanges 8 of the bosses 7, and said screws engage internally screw threaded bosses 19. A plate 20 which is positioned between the heel carrying base 2 and the leather heel lift 3, carries the bosses 19, and said bosses extend downwardly from the plate through the heel lift.

In Figure 6, the rubber heel 4 is also shown secured in place by screws, and the heads 21 of these screws 22 contact with the flanges 8 of the bosses 7. The screws 22 engage internally screw threaded hollow bolts 23 which pass downwardly through the heel carrying base 2 and the leather heel lift 3.

When the metal plate 5 is exposed as the result of the wearing away of the rubber heel 4, it provides a smooth wear resisting surface that will not scratch or otherwise mar floors and floor coverings. The vertical dimension of the bosses 7 is greater than the corresponding dimension of the heads of the elements securing the rubber heel 4 in place. In view thereof, the heads of the securing elements are located above the metal plate 5. All possibility of any projection of the heads below the metal plate 5 is thus avoided. The heads of the attaching elements cannot scratch or otherwise mar floors and floor coverings, especially when the

plate is exposed as the result of the wearing away of the rubber heel 4, and there is no possibility of the attaching elements, especially the nails 11 from being forced upwardly into the boot or shoe.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

A rubber heel having a metal anchoring and reenforcing plate embedded therein, said plate being provided with upstanding hollow bosses provided at their upper ends with interior annular flanges, the bosses terminating short of the upper side of the heel and portions of said side of the heel extending across and contacting with the upper ends of the bosses and their flanges, and attaching elements for securing the heel in place passing through the bosses and having their heads arranged completely above the lower surface of the said plate and in contact with the under sides of said flanges, said construction preventing contact of the heads with a floor should the plate become exposed, and openings being formed in the rubber heel below and in alignment with the bosses.

In testimony whereof I affix my signature.

NAPOLEON B. RIDDLE.
